(57) **CLAIM**

The ornamental design for smart glasses, as shown and described.

DESCRIPTION

FIG. 1 is an upper-front-right perspective view of smart glasses according to the present invention;

FIG. 2 is an upper-rear perspective view of the smart glasses of FIG. 1;

FIG. 3 is a front view of the smart glasses of FIG. 1;

FIG. 4 is a rear view of the smart glasses of FIG. 1;

FIG. 5 is a left view of the smart glasses of FIG. 1;

FIG. 6 is a right view of the smart glasses of FIG. 1;

FIG. 7 is a top-down view of the smart glasses of FIG. 1; and,

FIG. 8 is a bottom-up view of the smart glasses of FIG. 1. The broken lines shown in the figures depict portions of the smart glasses that form no part of the claimed design.

1 Claim, 5 Drawing Sheets

UNITED STATES PATENT AND TRADEMARK OFFICE
CERTIFICATE OF CORRECTION

PATENT NO. : D1,020,847 S
APPLICATION NO. : 29/818584
DATED : April 2, 2024
INVENTOR(S) : Yue He et al.

Page 1 of 1

It is certified that error appears in the above-identified patent and that said Letters Patent is hereby corrected as shown below:

On the Title Page

Item [73], delete:
“Matrixed Reality Technology Co.. Ltd.”
And insert:
--Matrixed Reality Technology Co., Ltd.--

Signed and Sealed this
Eighteenth Day of June, 2024
